UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

APPARATUS FOR AND METHOD OF MAKING CRINKLED FABRIC.

Application filed December 20, 1919. Serial No. 346,310.

To all whom it may concern:

Be it known that I, WILLIAM A. LORENZ, a citizen of the United States, residing in Hartford, in the county of Hartford and 5 State of Connecticut, have invented certain new and useful Improvements in Apparatus for and Methods of Making Crinkled Fabric, of which the following is a specification.

This invention relates to the crinkling of paper, etc.

An object of the invention is to crinkle paper and other fabric in such a manner that it will be elastic or yielding in all directions and possess other valuable properties.

To this end the paper or fabric, which may be in the form of a web, is led from a supply roll or spool between formers, which 20 may consist of sets of bars or ribs, which corrugate the web longitudinally. The web may then be led around a cylinder, to which it may be caused to cling by the use of a vacuum appliance. The cylinder has 25 grooves into which the corrugations of the paper fit. The paper is advanced edge foremost against a crimping obstruction in the form of a doctor blade, which strips the web from the cylinder and in so doing crinkles 30 the web transversely. The doctor blade has teeth which mesh into the grooves in the cylinder, so that all portions of the web are transversely crinkled; that is, not only the tops and bottoms of the ridges or flutes, but 35 also the intervening portions, so that the web is entirely crinkled, and the product is therefore a crinkled web in which the crinkles undulate or form waves continuously across the sheet. This paper or other fabric is 40 elastic in all directions, and is capable of a wide range of use.

Other features and advantages will hereinafter appear.

In the accompanying drawings,

Figure 1 represents a plan view of the apparatus to carry out the process.

Figure 2 is a central longitudinal view on the line 2-2 of Figure 1.

Figure 3 is a front view looking in the direction of the crinkling blade and the grooved cylinder.

Figure 4 shows a sectional view on an enlarged scale of a portion of the cylinder, the crinkling blade and the roll adjacent to that 55 blade, taken on the line 2-2 of Figure 1.

Figure 5 shows a sectional view on the line 7-7 of Figure 1, showing a portion of the fluting blade.

Figure 6 shows a plan view and

Figure 7 a side view of the steps in the 60 process of forming this paper.

Figure 8 shows a section on the line 8-8 of Figure 6 of a portion of a sheet of paper.

Figure 9 is a section on the line 9-9 of Figure 6, showing the fluting or grooving. 65

Figure 10 shows a section on the line 10-10 of Figure 6, showing the crinkled paper.

Figure 11 is a full-size view of part of a 70 sheet produced by the novel method.

The paper or other web to be treated may be led (preferably in dry condition) from a supply spool 10, rotation of which may be retarded by a brake device, comprising an inclined strap 11 suspended from a fixture 12 and pulled down by a weight 13. The paper is led from this supply roll over a roll or drum 14, which guides the paper into the jaws of a forming device, comprising co-operative ribbed plates 15, 16, whereby the web 75 is longitudinally corrugated or fluted preparatory to being transversely crimped or crinkled. These forming plates, which may be supported by means of bars 17 upon the side arms 18 of the machine, have sets of 80 converging ribs 17^a formed in their opposing faces, the ribs being shown in cross-section at Figure 5, and their converging arrangement being shown in plan at Figure 1. The ribs in one set extend into the grooves 85 between the ribs of the other set, so as to give the paper the desired corrugation. As the web advances, the corrugations formed are at first shallow and finally deep, this deepening being due to the relative sloping arrangement of the ribs or formers, one set being inclined relatively to the other set. The extent to which the ribs in one set sink into the grooves in the other set is least at the receiving end and greatest at the emergent 90 end of the forming plates, whereby the fabric is gradually contracted in width and changed from the flat form into the deeply and smoothly or evenly corrugated web seen at 19, Figure 5.

The fabric is considerably contracted in width upon emerging from the corrugating plates 15, 16. It may be led over the top of a guide roll 21, upon which preferably runs a companion roll 20, both rolls being 95 100 105 110

- vided with peripheral grooves 21^a that may correspond or agree with the corrugations that have been made in the paper by the plates 15, 16. The upper roll 20 may aid in drawing the web through the plates 15, 16 against the opposition of the brake 11, and in making the necessary bend of the corrugated and therefore stiffened paper around the comparatively small roll 21.
- 10 The ribs on one roll run in the grooves on the other, and may be so formed as either to complete the corrugating or fluting of the web, or to preserve the fluting as it comes from the plates 15, 16.
- 15 By the roll 21 the corrugated web may be delivered to a relatively large power-revolved hollow main cylinder or drum 22, having peripheral grooves 23 to correspond with those of the rolls 20 and 21, so that the
- 20 flutes and ridges in the corrugated paper fit into the contour of the main cylinder. Roll 21 may be juxtaposed to or press against the main cylinder 22, at the point where the corrugated paper leaves 21 to curve in the re-
- 25 verse direction around the under side of cylinder 22, the ribs on 21 preferably meshing with those on 22, these rolls co-operating to grip the corrugated paper at this point where the reverse bend begins, and the roll
- 30 21 being driven in any suitable way, as, for example, by cylinder 22, and this may be effected either through both the longitudinal pull upon the web and the pressure of one roll against the other or in any other
- 35 suitable way.

Said main cylinder 22 therefore draws the paper off from the retarded supply 10, and around the guide roll 14 and through the fluters 15, 16, and also around the roll 21; and said cylinder 22 also effects the transverse crimping of the corrugated or fluted web.

- 40 By reason of the stiffened condition of the corrugated web, it resists being bent closely around cylinder 22, and tends to bulge away from the same. To overcome this tendency, and insure that the web shall bend closely around the cylinder and cling thereto at all points, so that the cylinder may exert the desired control over the web, there is provided means for exhausting the air from within the stiffened web, whereby it is pinched against the cylinder by atmospheric pressure. For this purpose there is preferably employed a vacuum box 25, from which air is exhausted through a pipe 26. This vacuum box is stationary and conforms to the curvature of cylinder 22 and is open only upon the cylinder side. One side of
- 45 the box extends at 27 far into the bight of roll 21 with cylinder 22; and the opposite side of the box has a side portion or member 30, having a corresponding relation with the bight of said cylinder with a delivery roll 33, presently to be described, so that ex-

haustion of the air from the box produces a partial vacuum between the web and the cylinder 22, thus permitting the stiffened web to be pressed at all points firmly against the cylinder by the atmosphere. The edge portion of the box at 27 may be provided upon its outer side with grooves and ridges to fit the corrugations in the web, or with teeth (similar to 31 at Figure 3) to lie within the troughs in the web, so that this box edge 75 may lie close against the web upon the roll 21, to exclude the air, thus conducting to the successful exhaustion of air from between the web and the cylinder 22, at the point where the web advances upon the cylinder, 80 so that this portion of the web is at once pinched against the cylinder by the atmosphere, which maintains its control until the point is reached where the web is to be stripped from the cylinder.

85 The opposite side of the box comprises said member 30, which, as seen at Figures 3 and 4, is in the nature of a metal blade formed with teeth 31, which fit into the grooves 23 upon the cylinder 22 with sufficient tightness to permit the required partial vacuum to be made within the web as it advances upon the cylinder 22.

90 Close to said blade 30, which is termed a doctor blade, may be mounted a web-feeding or pressure roll 33 (driven by any suitable means), which has peripheral grooves 34 to match the corrugations in the web and to co-operate with the cylinder 22 to hold the web firmly where the latter 100 encounters the doctor blade or obstruction 30. The periphery of the roll 33 may be made of soft rubber or other elastic material if desired. The pressure exerted by the atmosphere in holding the web against the cylinder and the force of the feeding roll 33 may be relied upon to urge or force the leading portion of the advancing web edge-wise against the lower part of the stationary doctor blade, to enable the latter to strip the web from the cylinder by a web-crimping action; so that the web as it strips from the cylinder is crimped or crinkled by the co-operation of the blade with the cylinder and the roll 33. The roll 33 may have a smooth face if desired, i. e., it may be plain or uncorrugated. The front face of the tangent doctor blade 30 may be made entirely straight, or it may be beveled or formed at an angle at its lower edge, so as to hold back the paper which runs across its face in order to crinkle it, as shown at 110 35, Figure 4.

115 The originally corrugated paper is thus formed with crinkles which conform generally to the corrugations and therefore extend in undulations across the web. In other words, the crinkling or crimpling extends into the grooving or corrugations, so that the product is crinkled over its entire

surface, as set forth in my co-pending application No. 333,750, filed October 27, 1919, which covers the novel product herein disclosed. The proportion of the grooving 5 in width and depth may be made as desired, either coarse or fine, in the rolls and cylinder, as well as in grooving plates. The vacuum which is maintained during the crimping operation may be varied according 10 to the thickness or quality of the paper to be crimped. The crinkled paper emerges over delivery rolls or belts 36.

The process is illustrated in Figures 6 to 15, in which the width of the original web is shown at 50 (enlarged in Figure 8), which is contracted from 51 to the width desired as at 52 (enlarged in Figure 9). Then the paper passes around the roll 21 as at 53, and then around the cylinder 22 as at 54, and 20 under the pressure roll 33 as at 55. There it emerges against the doctor blade or crimper as at 56, and becomes crinkled and is delivered as at 57.

The paper may be dry throughout the 25 entire operation, but in some cases it is desirable to moisten the paper slightly, and this may be done either by the use of steam, or by means of an atomizing device on either side of the web, or on both sides. 30 There is illustrated a sprinkling pipe 58, Figure 2, extending along the web at one side to moisten the same. There is also shown a sprinkling pipe 59 extending across the web on the other side, so that either one 35 or both sides may be watered or moistened. Preferably, the moistened paper is dried while in the machine, and for this purpose the cylinder 22 may be heated, so that the paper, in passing over the hot cylinder, 40 will be delivered dry or nearly so, its condition depending upon the degree of heat and the diameter of the cylinder. The corrugations and crinkles in the product will be stiffer and stand up better, and will also be 45 more elastic and hold better against the tendency to stretch, if the crinkling is done while the paper is hot. The cylinder may be heated by a steam pipe 60 entering through the end of a hollow axle 61 which 50 supports the cylinder. Condensation in the cylinder may be drained through a pipe 63 at the other end of the hollow axle. The product, as set forth in said application, is 55 elastic in all directions, owing to the undulatory character of the crinkling; and the elasticity is increased by drying the dampened paper at the crinkling operation, as above explained.

Any other suitable means may be employed for forming the web into longitudinal grooves, as at 52, and the paper thus grooved may be passed either around the cylinder 22, or in a straight line, or otherwise against a doctor blade, to form the paper in fine 60 transverse crinkles which undulate or fol-

low the general contour of the grooves or waves.

At Figure 10, which is an enlarged sectional view on the line 10—10 of Figure 6, is shown diagrammatically the irregular 70 crinkling that is produced in the fabric. It will be observed that the longitudinal corrugations which are originally made in the web, as at Figure 9, will be converted into crinkled or irregular troughs and ridges 75 or ribs.

The speed of the machine may be varied and thereby the crinkling may be modified, a low speed tending to make the crinkles sharp and deep, while high speed tends to 80 make them shallow and open. In this and other ways, various designs in crinkling may be produced, coarse or fine. Variation in the appearance of the crinkling may also be made by making the front face of the doctor 85 blade more or less abrupt. Variations in the crinkling may also be produced by varying the degree of vacuum in the vacuum box, so as to cause the atmosphere to hold the stiffened web more or less closely to the 90 cylinder 22, and urge it with more or less force against the doctor blade or crinkling device 30. The paper may be crinkled dry if preferred, but if it is made slightly moist and then dried upon the heated cylinder during the crinkling operation, the crinkled paper will be more elastic. It will not be 95 usually desirable to take the preliminary step of dipping the paper into a saturating water bath, which would be liable to weaken the paper permanently. The invention is not limited to moistening the paper after the corrugating operation, since it is often desirable to effect the moistening before (or 100 during) corrugation thereof, on one or both 105 sides.

I am aware of the British patent to Parrish, No. 1610 of 1871, covering wrinkled paper which is corrugated transversely to the wrinkles, to render the paper elastic in 110 all directions, said patent setting forth:

"The corrugations or wrinkles in the sheet are all in one direction, so that the sheet is elastic only in the opposite direction, but by passing the sheet through or between a pair of corrugated or wrinkled rollers or plates in the opposite direction the sheet can be made elastic all ways."

The invention herein disclosed is manifestly distinct from the process of said Parrish patent, since my novel undulatingly crinkled sheet and my novel process possess obvious advantages over the process disclosed by Parrish of modifying paper which has originally been crinkled in one direction by passing it between corrugated rolls which then corrugate the paper in the other direction.

It will be seen that the process of forming elastic paper or fabric which is elastic in all 130

directions, comprises narrowing the width of the web or sheet by producing longitudinal grooves or corrugations therein, then moving the web so corrugated against an 5 obstruction in the form of a doctor blade, which converts the corrugated web into material in which crinkles run in waves across the web, conforming more or less closely to the waves or corrugations which are originally 10 made in the web, whereby the smooth wave-like corrugations are converted into crinkled corrugations. The invention, however, is not limited to the process of reducing the width of the web. Any suitable paper 15 or web may be employed, such as sulphite or wood-pulp or kraft papers.

Variations may be resorted to within the scope of the invention, and portions of the improvements may be used without others.

20 Having thus described my invention, I claim:

1. The process of forming paper or fabric elastic in all directions, consisting in corrugating a web or sheet longitudinally, thereby 25 reducing it in width, and advancing the corrugated paper edgewise in the direction of the corrugations while obstructing it at its leading portion, to crinkle the sheet transversely of the corrugations, with the 30 crinkles conforming generally to the contour of said corrugations.
2. The process of making a paper elastic in all directions, comprising forming the paper in longitudinal corrugations and advancing the paper in the direction of the corrugations while preserving the corrugated condition of the paper by unsupported 35 atmospheric pressure thereon, while obstructing its path to crinkle the corrugations transversely of their length.
3. The process of making a paper elastic in all directions, comprising, first, forming the paper into longitudinal grooves, and, second, forming the grooves and corrugations into minute crinkles throughout.
4. The process of making a paper elastic in all directions, comprising, first, forming the paper into longitudinal grooves, and, second, forming the grooves and corrugations into minute crinkles throughout, by advancing the paper edgewise in the direction of the grooves while obstructing its path.
5. The process of forming in a sheet longitudinal corrugations, moistening the sheet, and advancing the sheet while obstructing its leading edge or portion to form it into transverse crinkles, and simultaneously heating the sheet.
6. The process of advancing corrugated paper or fabric in the direction of the corrugations while obstructing at all points the path of the advancing fabric, to crinkle it throughout its corrugations in lines transverse thereto.

7. The process of advancing moistened corrugated paper or fabric in the direction of the corrugations while obstructing at all points the path of the advancing fabric, to crinkle it throughout its corrugations in 70 lines transverse thereto.

8. The process of advancing moistened corrugated paper or fabric in the direction of the corrugations while obstructing at all points the path of the advancing fabric, to 75 crinkle it throughout its corrugations in lines transverse thereto, and heating the paper to dry it at the crinkling operation.

9. The process of making the hereinbefore-described fabric, comprising, first, producing corrugations in the fabric, and, second, advancing the corrugated sheet in a direction longitudinal of the corrugations, while obstructing the advance of the fabric at its leading edge or portion in a manner to 80 crinkle the fabric throughout said corrugations, the crinkles being transverse to the corrugations.

10. The process of making the hereinbefore-described fabric, comprising, first, producing corrugations in the fabric, and, second, advancing the corrugated sheet in a direction longitudinal of the corrugations, while obstructing the advance of the fabric at its leading edge or portion in a manner to 90 crinkle the fabric throughout said corrugations, the crinkles being transverse to the corrugations, moistening the paper preparatory to the crinkling operation.

11. The process of making the hereinbefore-described fabric, comprising, first, producing corrugations in the fabric, and, second, advancing the corrugated sheet in a direction longitudinal of the corrugations, while obstructing the advance of the fabric 100 at its leading edge or portion in a manner to crinkle the fabric throughout said corrugations, the crinkles being transverse to the corrugations, moistening the paper preparatory to the crinkling operation, and heating the paper to dry it at the crinkling operation.

12. The process of producing a paper elastic in all directions, comprising longitudinally corrugating a web and reducing 115 its width, advancing the paper and bending it facewise first in one direction and then in the other as it advances, and obstructing its leading edge to effect crimping thereof throughout the corrugations.

13. The process of producing a paper elastic in all directions, comprising longitudinally corrugating a web and reducing its width, advancing the paper and bending it facewise first in one direction and then in 125 the other by atmospheric pressure as it advances, and obstructing its leading edge to effect crimping thereof throughout the corrugations.

14. The process of making a paper elas-

tic in all directions, comprising longitudinally corrugating the web, dampening the web, heating the web, and obstructing its leading edge to crinkle it transversely entirely across the corrugations.

15. The combination of means for longitudinally corrugating a paper or fabric, means for advancing the paper through the corrugating means, means for retarding the paper as it is led into said corrugating means, and means for obstructing the corrugated paper to crinkle it throughout its corrugations transversely thereof.

16. The combination of means for longitudinally corrugating a paper or fabric, means for advancing the paper through the corrugating means, means for retarding the paper as it is led into said corrugating means, and means for obstructing the corrugated paper to crinkle it throughout its corrugations transversely thereof, said corrugating means comprising opposite sets of convergent forming bars or ribs, the ribs in one set meshing with those in the other set.

25 17. The combination of means for longitudinally corrugating a web, a pair of feed-rolls at the delivery side of said corrugating means, said rolls having meshing peripheral ribs to correspond to the corrugations in the web, a main cylinder upon which one of said rolls runs, said main cylinder being peripherally grooved, a doctor blade having teeth inserted in the grooves in said main cylinder, and a feed-roll running upon said main cylinder in proximity to said doctor blade.

18. The combination of means for longitudinally corrugating a web, a pair of feed-rolls at the delivery side of said corrugating means, said rolls having meshing peripheral ribs to correspond to the corrugations in the web, a main cylinder upon which one of said rolls runs, said main cylinder being peripherally grooved, a doctor blade having teeth inserted in the grooves in said main cylinder, and a feed-roll running upon said main cylinder in proximity to said doctor blade, means being provided for exhausting air to cause the atmosphere to press the corrugated web into the grooves upon the main cylinder.

19. The combination of means for longitudinally corrugating a web, a pair of feed-rolls at the delivery side of said corrugating means, said rolls having meshing peripheral ribs to correspond to the corrugations in the web, a main cylinder upon which one of said rolls runs, said main cylinder being peripherally grooved, a doctor blade having teeth inserted in the grooves in said main cylinder, and a feed-roll running upon said main cylinder in proximity to said doctor blade, means being provided for exhausting air to cause the atmosphere to press the corrugated web into the grooves upon the

main cylinder, said exhausting means comprising a vacuum box fitting around the periphery of said cylinder and open at said periphery and comprising said doctor blade, the teeth on the blade obstructing the inflow of air.

20. The combination of means for narrowing a sheet or web by producing longitudinal corrugations therein, means for advancing the corrugated web, and means, including a serrated doctor blade, for obstructing the advance of the web in a manner to convert it into transversely crinkled material, with the crinkles conforming generally to the corrugations.

21. The combination with a doctor blade having serrations, of means for advancing a corrugated fabric in the direction of the corrugations edgewise upon or against said doctor blade at its serrations, to convert the fabric into transversely crinkled material elastic in all directions, with the crinkles conforming generally to the contour of the original corrugations.

22. The combination of means for narrowing a web by forming longitudinal corrugations therein, a corrugated cylinder over which the web is led, means for exhausting air to enable the atmosphere to pinch the web against the cylinder, a doctor blade and means to co-operate with said cylinder to force the leading end or portion of the web against the doctor blade, to crinkle the paper by converting the smooth wave-like corrugations into crinkled wave-like corrugations.

23. The combination of a device for forming a web into longitudinal corrugations, a peripherally grooved roll over which the web is led, a main cylinder having peripheral grooves to correspond with the corrugations in the web, the ribs on said main cylinder running in mesh with those on said grooved roll, a doctor blade mounted at the delivery side of said cylinder and having teeth to enter the grooves in the main cylinder, and a feeding roll running upon the main cylinder in proximity to said doctor blade.

24. The combination of a device for forming a web into longitudinal corrugations, a peripherally grooved roll over which the web is led, a main cylinder having peripheral grooves to correspond with the corrugations in the web, the ribs on said main cylinder running in mesh with those on said grooved roll, means for exhausting air to cause the atmosphere to press the web against the cylinder, a doctor blade mounted at the delivery side of said cylinder and having teeth to enter the grooves in the main cylinder, and a feeding roll running upon the main cylinder in proximity to said doctor blade.

25. The combination of a device for form-

- ing a web into longitudinal corrugations, a peripherally grooved roll over which the web is led, a main cylinder having peripheral grooves to correspond with the corrugations in the web, the ribs on said main cylinder running in mesh with those on said grooved roll, a doctor blade mounted at the delivery side of said cylinder and having teeth to enter the grooves in the main cylinder, a feeding roll running upon the main cylinder in proximity to said doctor blade, and means for dampening the paper preparatory to advancing around said main cylinder.
15. 26. The combination of a device for forming a web into longitudinal corrugations, a peripherally grooved roll over which the web is led, a main cylinder having peripheral grooves to correspond with the corrugations in the web, the ribs on said main cylinder running in mesh with those on said grooved roll, a doctor blade mounted at the delivery side of said cylinder and having teeth to enter the grooves in the main cylinder, a feeding roll running upon the main cylinder in proximity to said doctor blade, means for dampening the paper preparatory to advancing around said main cylinder, and means for heating the cylinder.
20. 27. The combination of a device for forming a web into longitudinal corrugations, a cylinder having peripheral grooves to correspond with the corrugations in the web, a doctor blade mounted at the delivery side of said cylinder and having teeth to enter the grooves in the cylinder, and means to co-operate with the doctor blade to crinkle the paper.
25. 28. The combination of a device for forming a web into longitudinal corrugations, a cylinder having peripheral grooves to correspond with the corrugations in the web, means for exhausting air to cause the atmosphere to press the web against the cylinder, a doctor blade mounted at the delivery side of said cylinder and having teeth to enter the grooves in the cylinder, and means to co-operate with the doctor blade to crinkle the paper.
30. 29. The combination of a device for forming a web into longitudinal corrugations, a cylinder having peripheral grooves to correspond with the corrugations in the web, a doctor blade mounted at the delivery side of said cylinder and having teeth to enter the grooves in the cylinder, means to co-operate with the doctor blade to crinkle the paper, and means for heating the cylinder.
35. 30. The combination of a supply-roll, a guide-roll over which a web is led from the supply-roll, a device for forming the web into longitudinal corrugations, a peripherally grooved feeding roll between which the web is led, a main cylinder peripherally grooved to correspond with the corrugations of the web, means for exhausting air to cause the atmosphere to press the web against the cylinder, a doctor blade mounted at the delivery side of said cylinder and having teeth to enter the grooves in the main cylinder, and a peripherally grooved elastic feeding roll running upon the main cylinder in proximity to said doctor blade.
40. 31. The combination of a supply-roll, a brake therefor, a guide-roll over which a web is led from the supply-roll, a device for forming the web into longitudinal corrugations, comprising opposite plates having converging ribs or bars on each plate sloping into the grooves in the other plate, peripherally grooved feed-rolls between which the web is led from said plates, a main cylinder having a peripheral groove to correspond with the corrugations of the web, the ribs on said main cylinder running in mesh with those on one of said feed-rolls, means for exhausting air between the web and the main cylinder, to cause the atmosphere to press the web against the cylinder, said exhausting means comprising a vacuum box having a side which extends into the bight of said cylinder and its said feed-roll, said side being toothed to enter the grooves in the feed-roll to obstruct the inflow of air, a doctor blade mounted at the delivery side of said cylinder and forming a part of said vacuum box and having teeth to enter the grooves in the main cylinder, a peripherally grooved feeding-roll running upon the main cylinder in proximity to said doctor blade, and having an elastic surface, said doctor blade having its toothed portion at an angle, to hold back the advancing paper and crinkle it, in both grooves and ridges, means for dampening the paper on both sides preparatory to advancing it around said main cylinder, and means for heating the cylinder to dry the paper.
45. 32. The combination of means for longitudinally corrugating a web of paper or the like, means for heating the paper, and means for obstructing the corrugated heated paper to crinkle it throughout its corrugations transversely thereof.
50. 33. The combination of means for longitudinally corrugating a web of paper or the like, means for moistening the paper, means for heating the paper, and means for obstructing the corrugated heated paper to crinkle it throughout its corrugations transversely thereof.
55. 34. Apparatus for making stretchable paper, comprising a rotatable drum having a suction box associated therewith and operative upon the surface thereof, and a doctor co-operative with said drum, said drum, suction box and doctor having a construction and relative arrangement for crinkling the paper web both transversely and longitudinally.

35. In an apparatus for operating on paper, the combination of a supporting surface for the paper having grooves therein parallel with the direction of travel of the paper and a crinkle-forming abutment having serrations fitting into said grooves.
36. The process in the art of making paper which consists in longitudinally corrugating a web and advancing the web while obstructing its path and while maintaining it in corrugated condition to crinkle the corrugations transversely.
